(57) **CLAIM**

The ornamental design for a handle of a toy wand, as shown and described.

DESCRIPTION

FIG. 1 is a front view of a handle of a toy wand;
FIG. 2 is a back view of the handle of a toy wand;
FIG. 3 is a left side view of the handle of a toy wand;
FIG. 4 is a right side view of the handle of a toy wand;
FIG. 5 is a top view of the handle of a toy wand; and,
FIG. 6 is a bottom view of the handle of a toy wand.
The broken lines show portions of the handle of a toy wand that form no part of the claimed design.

1 Claim, 6 Drawing Sheets
